UNITED STATES PATENT OFFICE

156,258

DESIGN FOR A ROAD SIGNAL

Emile A. Lieutard, San Francisco, Calif.

Application April 27, 1949, Serial No. 2,294

Term of patent 14 years

(Cl. D72—1)

To all whom it may concern:

Be it known that I, Emile A. Lieutard, a citizen of the United States of America, residing at San Francisco, in the county of San Francisco and State of California, have invented a new, original, and ornamental Design for a Road Signal, of which the following is a specification, reference being made to the accompanying drawing, forming a part thereof.

Fig. 1 is a front elevational view of a road signal showing my new design;

Fig. 2 is a top plan view thereof; and

Fig. 3 is a front perspective view.

The characteristic features of my design reside in those portions shown by means of full lines in the drawing. Also, the back of the device is the same as shown in Fig. 1.

I claim:

The ornamental design for a road signal, substantially as shown and described.

EMILE A. LIEUTARD.
